REMOTE DICTATION SYSTEM

Lloyd R. Jones, Monroe, Rudolf E. Freund and John M. Raynor, Bridgeport, and Douglas E. Taylor, Westport, Conn., assignors to Dictaphone Corporation, Bridgeport, Conn.

Application March 28, 1957, Serial No. 649,066

23 Claims. (Cl. 179—100.1)

This invention relates to dictating apparatus. More particularly, this invention relates to remotely-operated dictation systems wherein a number of dictating stations are connected to central recording apparatus, e.g. as disclosed in U.S. patent application Serial No. 457,165, filed by Lloyd R. Jones and Douglas E. Taylor on September 20, 1954. The description herein is directed primarily to improvements over this earlier system, and similar nomenclature has been used to simplify comparison therewith. For detailed information on parts of the system not specifically disclosed herein, reference is made to the above application.

To obtain high-quality recording and reproducing, it is particularly important that the talking circuit between the dictating stations and the central machine be arranged to minimize the effects of extraneous signals such as electrostatic and electromagnetic pickup. This problem is particularly difficult in remote-dictation systems since it is desirable in such systems, as disclosed in the above application, to use the talking circuit for transmitting control information, e.g. in the form of multi-level direct-current signals. It is an important object of the present invention to solve this problem by providing novel circuit arrangements for accomplishing these objectives in a simple and economical manner. Further objects of the invention relate to the providing of improved control functions for facilitating the operation of a remotely-operated dictating machine. Other objects, aspects and advantages of the invention will be in part pointed out in, and in part apparent from, the following description considered together with the accompanying drawings in which:

Figure 1 is a schematic diagram of a remote dictation system comprising a preferred embodiment of this invention; and

Figure 2 is a schematic diagram of the remote dictator's instrument used in the system of Figure 1.

In the upper left-hand corner of Figure 1 is shown a telephone-type dictator's instrument indicated by a block 10, and which is similar in many respects to the corresponding instrument disclosed in the above application. This instrument, the details of which are shown in Figure 2, is connected by a cable having four lines 12, 14, 16 and 18 to a control unit including a number of relays which selectively condition a dictating machine generally indicated at 20 (see the right-hand portion of the drawing) for operation as desired by the remote dictator. (To simplify the discussion to follow, all of the relays are shown in their de-energized condition.)

As explained in the above application, a dictator may take control of the central machine 20 by lifting the hand-set of his instrument out of the cradle. This completes a direct-current path within the instrument 10 between lines 12 and 14 which constitute the talking circuit of the system. The direct-current path may be traced (Figure 2) from line 12 through a "length-of-letter mark" switch 22, contacts 24 and 26 of a "privacy"

2

relay generally indicated at 28, a resistor 30, through the carbon-button microphone 32, across contacts 34 and 36 of an "attendant's call" switch generally indicated at 38, across contacts 40 and 42 of the privacy relay, and through contacts 44 of a "cradle" switch generally indicated at 46 (which is actuated when the hand-set is lifted up) back to line 14.

Outside of the dictator's instrument (Figure 1), line 12 is connected through a lead 48 and the winding of a "line" relay 50 to the positive terminal of a D.C. power supply generally indicated at 52, and from the negative terminal of this power supply back through the winding of a "record" relay 54 and a lead 56 to line 14. Accordingly, the power supply 52 produces a flow of direct current through these two relays, which have identical windings, i.e. the same number of turns with the same ohmic resistance, and are balanced symmetrically about the power supply 52 in order to minimize stray electrical pickup in the talking circuit 12 and 14 due to external influences.

The line and record relays 50 and 54 are arranged to operate at different current levels, by virtue of differences in their contact spring loading and air gap spacing. The electrical specifications for the line relay are: (1) there will be no operation of the relay with a current through its winding of 3 milliamps., (2) the relay will operate with a current of 7 milliamps., (3) once the relay has pulled in, it will remain held in operated condition with a current of 4 milliamps., and (4) the relay will release when the current drops to 0.5 milliamp. Corresponding electrical specifications for the record relay are as follows: (1) there will be no operation of the relay with a current of 13 milliamps., (2) the relay will operate with a current of 16 milliamps., (3) once the relay has pulled in, it will remain held in operated condition with a current of 13 milliamps., and (4) the relay will release when the current drops to 8 milliamps.

As noted above, the D.C. current path established when the dictator picks up his hand-set includes a series resistor 30. This resistor is of relatively high ohmic resistance (3900 ohms) in order to establish a low steady-state current level of about several milliamps. Nevertheless, because of the circuit arrangement described below, the line relay 50 is actuated when the dictator lifts up his handset, and the machine 20 is conditioned for dictating operation from the dictator's instrument 10. When the dictator wishes to record, he depresses a clutch button 60 (normally part of the hand-set) which shorts out the resistor 30 through an inductor 62 and thereby establishes a current level in the talking circuit 12 and 14 sufficiently high to operate the record relay 54.

Reverting now to the condition with the hand-set out of its cradle and the clutch button 60 de-actuated, the steady-state current level established in the talking circuit due to the resistor 30 is too low normally to operate the line relay 50. However, it is not possible, as a practical matter, to reduce the size of the resistor 30 and still obtain an adequate differential between the two current levels established in the talking circuit, nor is it possible to increase the line voltage without introducing further complications in the system design. Also, the line relay cannot readily be made to operate at this low current level, particularly since its winding is identical to the record relay winding. Consequently, other means must be provided to assure that the line relay is actuated when the dictator lifts his hand-set.

This is accomplished in accordance with one aspect of the present invention by a capacitive circuit in parallel with the resistor 30. This capacitive circuit comprises a large capacitor 64 (having a capacitance of 10 micro-

farads) in series with a small resistor 66 (47 ohms). When the hand-set is lifted out of its cradle to complete the D.-C. path described above, this capacitive circuit initially presents an effective short circuit across the resistor 30 so that there is a momentary surge of current through the line relay 50 of sufficient magnitude to actuate this relay. This current surge is substantially equal in peak amplitude to the higher current level established when the resistor 30 is shorted out by the clutch button 60 (the series resistor 66 having only a minor effect on the current magnitude). It has been found that the record relay 54 will momentarily be actuated by this surge of current, but this has no important effect on the operation of the system.

When the line relay 50 is energized, its contacts 68 close to complete an energizing circuit for an "in-use" relay generally indicated at 70 (and corresponding to the second in-use relay 136 referred to in the above-mentioned prior application). The energizing circuit for relay 70 may be traced from a positive terminal 72 of a D.-C. power supply 74, through contacts 68 of the line relay, through a rectifier 76 and a resistor 78, through the in-use relay winding and back along a lead 80 to the negative terminal 82 of the power supply. Actuation of the in-use relay closes its contacts 84 to complete an energizing circuit for a "hold" relay generally indicated at 86, the circuit passing from the positive terminal 72 of the power supply 74 through the in-use relay contacts 84, through a resistor 88 and the hold relay winding, and back along lead 80 to the negative terminal 82 of the power supply.

Actuation of the hold relay 86 closes its contacts 90 which furnish A.-C. power to a motor 92 in the dictating machine 20. The rotor shaft of this motor is coupled to a clutch 94 to operate certain elements of the dictating machine in a manner well known in the art. The A.-C. power circuit completed by the hold relay also may be connected to the rectifier power supply typically provided in a dictating machine to furnish D.-C. plate potentials for the vacuum tubes of the audio amplifier.

To commence dictation, the dictator presses the clutch button 60 which as described above shorts out resistor 30 and increases the D.-C. current level flowing through the talking circuit to operate the record relay 54. Contacts 100 of this relay close and complete an energizing circuit to a clutch relay generally indicated at 102, the energizing current being delivered by the D.-C. power supply 74. Contacts 104 of the clutch relay thereupon close to complete an energizing circuit for a clutch solenoid generally indicated at 106 in the dictating machine 20. This energizing circuit may be traced from the positive terminal 72 of the D.-C. power supply 74, through contacts 100 of the record relay and contacts 104 of the clutch relay, through contacts 108 of a limit relay generally indicated at 110 (which as described in the above application is normally energized whenever the remote dictation system is available for use), through the clutch solenoid winding and back along a lead 114 to the negative terminal 82 of the D.-C. power supply. Energization of the clutch solenoid actuates the clutch 94 which thereupon transmits mechanical power from the motor 92 to the dictating machine drive mechanism. Accordingly, by conventional means not shown herein, the machine record belt 116 is caused to move past a recording head 118 in contact therewith, and the recording head carriage 120 is caused to traverse relative to the record belt.

Voice signals spoken into the microphone 32 are fed from the dictator's instrument 10 along the talking circuit lines 12 and 14 to the balanced primary windings 122 and 124 of an audio transformer generally indicated at 126; these windings are identical and are connected together through a D.-C. blocking capacitor 128. From the secondary winding 130 of this transformer, the voice signals are transmitted to the input terminals 132 and 70

134 of the machine 20 from which they are fed through a conventional amplifier (not shown in detail) the output circuit of which is coupled to the recording head 118. Consequently, the audio signals developed in the microphone 32 are impressed on the record belt 116.

Reverting now to the condition when a dictator has first picked up his hand-set, the consequent energization of the hold relay 86 closes its contacts 142 and completes an energizing circuit to feed D.-C. power to lines 16 and 18. This circuit may be traced from the negative terminal 144 of a D.-C. power supply 146 (lower left-hand corner of the drawing), through contacts 142 of the hold relay, through a fixed contact 148 and movable arm 150 of the limit relay 110 to line 16; and from line 18 to the positive terminal 152 of the power supply 146. As described in the above-mentioned application, this power energizes a lamp 154 (Figure 2) at each dictator's instrument 10 to indicate that the system has been seized for operation. In addition, the privacy relay 28 will be energized at the dictator's instruments that are not in use; the privacy relay at the station in use will not be energized because the relay energizing circuit is broken by contacts 156 of the cradle switch 46 which open when the hand-set is lifted out of its cradle.

The D.-C. power supply 146 includes a conventional full-wave rectifier circuit (not shown) the output of which is unfiltered so that the signal fed to lines 16 and 18 includes a substantial component of 120 cycle hum. Whenever a subsequent dictator picks up his hand-set while the system is in use, this hum component is fed to the ear-phone 158 of that dictator's instrument in order to warn him that the system is not available. The warning hum circuit may be traced from line 16 through contacts 160 of the cradle switch 46 (actuated when the subsequent dictator lifts his hand-set), through a fixed contact 162 and movable arm 40 of the privacy relay 28 (which is maintained in energized condition through locking contacts 164 of the privacy relay when the hand-set is lifted up), through the attendant's switch 38 to the ear-phone 158, through a capacitor 166 and a resistor 168, through movable arm 26 and a fixed contact 170 of the privacy relay, and through a capacitor 172 back to line 18.

To make a "length-of-letter mark" on the transcription pad normally provided with a dictating machine, the dictator depresses switch 22 in the instrument 10. This breaks the direct-current path for the talking circuit lines 12 and 14, and the line and record relays 50 and 54 accordingly are de-actuated. Contacts 68 of the line relay open to break the energizing circuit for the in-use relay 70; after a short time delay produced by a capacitor 174 (12 microfarads) in parallel with the winding of this relay, the in-use relay drops out and its contacts 84 open to de-energize the hold relay 86. The hold relay is of the "slow release" type because of a capacitor 176 (60 microfarads) in parallel with the relay winding, and the hold relay will not drop out until several seconds after the in-use relay contacts 84 have opened.

When the in-use relay 70 drops out, its contacts 178 close to complete an energizing circuit from a positive terminal 180 of the power supply 74, through contacts 182 of the hold relay (while it is held actuated by the capacitor 176) to a length-of-letter marking solenoid 184 in the dictating machine 20. The armature of this solenoid is mechanically connected to a marking device generally indicated at 186, the details of which form no part of the present invention, and which includes a marking stylus 188 arranged to make an indication mark on a pad of paper 190. The stylus 188, as usual, is mechanically driven along the pad 190 in accordance with the movements of the dictating machine carriage 120, as diagrammatically indicated by the dashed line connection 192; thus, the mark made by the stylus will indicate the positioning of the recording head at the time the mark is made.

The marking device 186, diagrammatically shown here,

in obtains its operating power from the output shaft of the clutch 94, as indicated by the dashed connection line 194. Since de-energization of the record relay 54 opens relay contacts 100 to break the normal energizing circuit for the clutch solenoid 106, an alternate energizing path for the clutch must be established whenever the length-of-letter mark switch 22 is depressed.

This is accomplished by a set of contacts 196 of the in-use relay 70 which close when the in-use relay drops out and thereby energize a tone relay 198. Contacts 200 of the tone relay close and establish an energizing circuit through a set of contacts 202 of the hold relay 86 (held actuated while the mark is made by capacitor 176) and contacts 108 of the limit relay to the clutch solenoid 106. Accordingly, the clutch 94 is energized and supplies power to the marking device 186 to make a single mark on the pad of paper 190.

The length-of-letter marking switch 22 is of the spring-loaded type, and in normal operation will break the talking circuit 12 and 14 only for a fraction of a second. The hold relay 86 is arranged so that it will not drop out until several seconds after it has been de-energized, and the length-of-letter mark will be made and the talking circuit re-established before the hold relay drops out. Therefore, the power circuit to lines 16 and 18 will remain activated and all of the privacy relays (except at the user's station) will remain energized. Consequently, the dictator cannot lose control of the machine 20 when he makes a length-of-letter mark, even if the hand-set at one of the other stations is out of its cradle.

As described in the above-mentioned application, when a dictator desires to listen back to a substantial portion of the material he has already recorded, he can signal the attendant at the central machine 20, and the attendant will thereupon manually move the machine carriage back to the desired region of the record and place the machine in "reproduce" condition. Because there is a possibility that a dictator, after listening to all of the recorded material on the record, may hang up his hand-set without having the machine returned to "record" condition, means also are provided in the present system to prevent any subsequent dictator from attempting to record additional material while the machine is in reproduce condition.

For this purpose, the machine carriage control lever diagrammatically indicated at 204 (and which is arranged by conventional means not shown herein to place the machine in "record," "neutral" or "reproduce" conditions) is mechanically connected to a cut-out switch 206 so as to close this switch whenever the machine is in reproduce condition, i.e. with the reproducing head 208 in contact with the record 116 and the recording head 118 out of contact with the record. When a dictator hangs up with the machine in this condition, the limit relay 110 will drop out because of a short-circuit placed across the relay winding. This short-circuit can be traced from the upper terminal of the relay winding through contacts 210 of the tone relay 198 (which is energized whenever the talking circuit 12 and 14 is interrupted) and back through the switch 206 to the lower terminal of the limit relay winding.

When the limit relay 110 drops out, it completes an energizing circuit from the power supply 146 through a fixed contact 212 and movable arm 150 of this relay to lines 16 and 18. Accordingly, the privacy relays for all of the dictator's instruments 10 will be energized, and it will not be possible for any remote dictator to take control of the machine 20. Also, the 120 cycle hum provided by the unfiltered output of the power supply 146 will be fed to the ear-phones of each of the dictator's instruments through the circuit previously described, so that any dictator who lifts his hand-set up will be positively warned that he cannot proceed with dictation until the machine has been reset for proper operation.

De-actuation of the limit relay 110 also causes a tone

signal to be sent to a loud-speaker 214 in the machine 20 to signify to the attendant that the machine must again be reconditioned for dictating operations. For this purpose, contacts 216 of the limit relay close to complete an energizing circuit from a positive terminal 218 of the power supply 74 to a pulse relay generally indicated at 220. Contacts 222 of the pulse relay close and activate a tone generator generally indicated at 224, the energizing current being supplied from another positive terminal 226 of the power supply 74. An audio-frequency tone signal thereupon is transmitted from the output terminals 228 of the tone generator, through a capacitor 230 and contacts 232 of the limit relay to the loud-speaker 214.

As described in the above-mentioned application, function controls are provided at the dictator's instrument 10 to enable the dictator to obtain playback operation (for purposes of obtaining a "quick review" of the last several words dictated), making a correction mark on the transcription pad associated with the dictating machine, and signalling the attendant. These functions are obtained in a similar manner in the present system by operating a "playback" push button 234, a "correction" push button 236, or the attendant's push button 38. Each of these push buttons close corresponding switch contacts which establish a direct-current path between lines 14 and 16, and thereby energize certain relays (not shown in detail herein to simplify the presentation) in the control unit which correspondingly operate the dictating machine 20 as desired. To exemplify this portion of the circuitry, there is shown in Figure 1 a control relay 238 (corresponding to control relay 362 in the above-mentioned prior application) which is connected between lines 14 and 16 and energized by a D.-C. power supply 240 when these lines are shorted together in the instrument 10. As explained in the above application, when the control relay is energized by operating the playback switch 234, it completes additional circuits (not shown) to condition the machine 20 for playback operation.

If lines 14 and 16 are connected directly together, an unbalanced condition would be established in the talking circuit 12 and 14. This can cause difficulty by permitting the flow of hum signals and other extraneous electrical pickup in the talking circuit, especially due to the 120 cycle hum signal fed to lines 16 and 18 by the unfiltered power supply 146. To avoid this difficulty, particularly when the machine is conditioned for playback operations, the direct-current connection between lines 14 and 16 (Figure 2) is made through a potentiometer 242. This potentiometer, in series with a D.-C. blocking capacitor 244 is effectively bridged across lines 12 and 14, and its slider 246 is connected to the lower switch sections 248 and 250 of the playback and correction push buttons 234 and 236. Thus, whenever either of these buttons is depressed, a direct-current path is established between line 14, through a portion of the potentiometer 242, through switch contacts 248 or 250 and back to line 16. By properly selecting the position of the slider of the potentiometer, the hum signal fed from lines 16 and 18 to the talking circuit 12 and 14 can be effectively balanced with respect to this latter circuit so as to substantially eliminate hum signals in the ear-phone 158.

Although a specific preferred embodiment of the invention has been set forth in detail, it is desired to emphasize that this is not intended to be exhaustive or necessarily limitative; on the contrary, the showing herein is for the purpose of illustrating one form of the invention and thus to enable others skilled in the art to adapt the invention in such ways as meet the requirements of particular applications, it being understood that various modifications may be made without departing from the scope of the invention as limited by the prior art.

We claim:

1. A remotely-operated dictation system which includes centrally-located recording and control apparatus

wherein a recording head is arranged for relative travelling movement with respect to a moving record, apparatus comprising, in combination, a plurality of remote dictator's instruments each including a transducer, a communication circuit for connecting said transducers to said recording and control apparatus, a voice-signal circuit coupled to said communication circuit for feeding the voice signals therein to said recording head, power supply means for producing current flow in said communication circuit, control means at each of said instruments for selectively establishing two different current conditions in said communication circuit, first and second current-energizable means connected in said communication circuit and selectively actuatable by said two current conditions respectively, circuit means for connecting said current energizable means in said communication circuit in balanced relationship both to said power supply means and to said voice-signal circuit, and operating means selectively under the control of said current-energizable means to establish predetermined control functions at said recording and control apparatus in accordance with the setting of said control means.

2. A remotely-operated dictation system which includes centrally-located recording and control apparatus wherein a recording head is arranged for relative travelling movement with respect to a moving record, apparatus comprising, in combination, a plurality of remote dictator's instruments each including a transducer, a communication circuit for connecting said transducers to said recording and control apparatus, power supply means for producing current flow in said communication circuit, control means at each of said instruments for selectively establishing two different steady-state current levels in said communication circuit, first and second relay means having their respective windings connected in series in said communication circuit, the lower of said two current levels being sufficient to hold said first relay means in operated condition but insufficient to hold said second relay means in operated condition, capacitive means forming part of said control means to produce an initial high-level surge of current in said communication circuit when said control means is operated to establish the lower of said two steady-state current levels, said high-level current surge being sufficient to operate said first relay means, and operating means selectively under the control of said relay means to establish predetermined control functions at said recording and control apparatus in accordance with the setting of said control means.

3. A dictation system as claimed in claim 2, wherein said first relay means is arranged when actuated to condition said recording apparatus for dictating operations.

4. A dictation system as claimed in claim 2, wherein the winding impedances of said first and second relay means are equal, and wherein the ratio of the "operate" to "release" currents of said first relay means is substantially higher than the ratio of the "operate" to "release" currents of said second relay means.

5. A remotely-operated dictation system which includes centrally-located recording and control apparatus wherein a recording head is arranged for relative travelling movement with respect to a moving record, apparatus comprising, in combination, a plurality of remote dictator's instruments each including a transducer and an on-off switch, a communication circuit for connecting said transducers to said recording and control apparatus, power supply means for producing current flow in said communication circuit when one of said on-off switches has been placed in "on" position, impedance means at each of said instruments for establishing a relatively low steady-state current level in said communication circuit, control switch means at each of said instruments for bypassing said impedance means to produce a relatively high steady-state current level in said communication circuit, first and second relay means having their windings connected in said communication circuit, said first relay

means being arranged so that it will hold in operated condition when the lower of said two steady-state current levels is established in said communication circuit, said second relay means being arranged so that it will not hold in operated condition when said lower current level is established but will operate when the higher of said levels is established, a reactive circuit connected to said impedance means to produce an initial high-level surge of current through said communication circuit when one of said on-off switches is first moved to "on" position, said first relay means being operable by said high-level current surge, and operating means selectively under the control of said current-energizable means to establish predetermined control functions at said recording and control apparatus in accordance with the setting of said control means.

6. A remotely-operated dictation system which includes centrally-located recording and control apparatus wherein a recording head is arranged for relative travelling movement with respect to a moving record, apparatus comprising, in combination, a plurality of remote dictator's instruments each including a microphone, a communication circuit for connecting said instruments to said recording and control apparatus, power supply means for producing current flow in said communication circuit, control means at each of said instruments and having first and second positions for selectively establishing two different current conditions in said communication circuit, first and second current-energizable means connected in said communication circuit and selectively actuatable by said two current conditions respectively, the electrical impedances of said current energizable means being substantially identical, circuit means for connecting said current energizable means in said communication circuit in balanced relationship to said power supply means, and operating means selectively under the control of said current-energizable means to perform corresponding control functions at said recording and control apparatus in accordance with the positioning of said control means.

7. A remotely-operated dictation system which includes centrally-located recording and control apparatus wherein a recording head is arranged for relative travelling movement with respect to a moving record, apparatus comprising, in combination, a plurality of remote dictator's instruments each including a microphone, a communication circuit comprising first and second lines for connecting said instruments to said recording and control apparatus, power supply means for producing current flow in said communication circuit, control means at each of said instruments and having first and second positions for selectively establishing two different current conditions in said communication circuit, first and second relay means connected in said first and second lines respectively and selectively actuatable by said two current conditions respectively, the windings of said relay means being substantially identical so as to present equal impedances in said lines, circuit means for connecting said power supply means between the windings of said first and second relay means in balanced relationship thereto, and operating means selectively under the control of said relay means to perform control functions at said recording and control apparatus in accordance with the positioning of said control means.

8. A remotely-operated dictation system which includes centrally-located recording and control apparatus wherein a recording head is arranged for relative travelling movement with respect to a moving record, apparatus comprising, in combination, a plurality of remote dictator's instruments each including a microphone and on-off switch means, circuit means for connecting any one of said instruments to said recording and control apparatus, said circuit means being completed when the on-off switch means at said one instrument has been placed in "on" position, privacy means at said instruments for excluding all other instruments from said re-

cording and control apparatus when said circuit means has been completed at one of said instruments, relay means responsive to the completion of said circuit means for actuating said privacy means, operating means connected to said circuit means and adapted to perform a predetermined function at said recording apparatus when said circuit means is momentarily interrupted, and time delay means for said relay means to prevent the de-actuation of said privacy means during the momentary interruption of said circuit means.

9. A remotely-operated dictation system which includes centrally-located recording and control apparatus wherein a recording head is arranged for relative travelling movement with respect to a moving record, apparatus comprising, in combination, a plurality of remote dictator's instruments each including a microphone and on-off switch means, circuit means for connecting any one of said instruments to said recording and control apparatus, said circuit means being completed when the on-off switch means at said one instrument has been placed in "on" position, privacy means at said instruments for excluding all other instruments from said recording and control apparatus when said circuit means has been completed at one of said instruments, relay means responsive to the completion of said circuit means for actuating said privacy means, marking means connected to said circuit means to make an indicating mark at said recording apparatus when said circuit means is momentarily interrupted, and time delay means for said relay means to prevent the de-actuation of said privacy means during the momentary interruption of said circuit means.

10. A remotely-operated dictation system which includes centrally-located recording and control apparatus wherein a recording head is arranged for relative travelling movement with respect to a moving record, apparatus comprising, in combination, a plurality of remote dictator's instruments each including a microphone and on-off switch means, circuit means for connecting any one of said instruments to said recording and control apparatus, said circuit means being completed when the on-off switch means at said one instrument has been placed in "on" position, privacy means at said instruments for excluding all other instruments from said recording and control apparatus when said circuit means has been completed to one of said instruments, relay means responsive to the completion of said circuit means for actuating said privacy means, control switch means at each of said instruments for momentarily interrupting said circuit means, operating means connected to said circuit means and adapted to perform a predetermined function at said recording apparatus when said circuit means is momentarily interrupted by said control switch means, and time delay means for said relay means to prevent the deactuation of said privacy means during the momentary interruption of said circuit means.

11. A remotely-operated dictation system which includes centrally-located recording and control apparatus wherein a recording head is arranged for relative travelling movement with respect to a moving record, apparatus comprising, in combination, a plurality of remote dictator's instruments each including a microphone and on-off switch means, communication and energizing circuits for connecting any one of said instruments to said recording and control apparatus, said communication circuit being completed when the on-off switch means at said one instrument has been placed in "on" position, a privacy relay at each of said instruments and arranged when actuated by said energizing circuit to exclude the respective instrument from said recording and control apparatus, control relay means, responsive to the completion of said communication circuit for activating said energizing circuit, circuit means forming part of each of said on-off switch means to disconnect the privacy relay corresponding to the respective instrument from said energizing circuit when said on-off switch means has been placed in

"on" position, a holding circuit for each privacy relay to by-pass the corresponding circuit means when the privacy relay is energized, operating means connected to said communication circuit and adapted to perform a predetermined function at said recording apparatus when said communication circuit is momentarily interrupted, and time delay means for said control relay means to prevent the de-actuation of said privacy means during said momentary interruption of said communication circuit.

10. A remotely-operated dictation system which includes centrally-located recording and control apparatus wherein a recording head is arranged for relative travelling movement with respect to a moving record, apparatus comprising, in combination, a plurality of remote dictator's instruments each including a microphone, switch means at each instrument for conditioning the instrument for dictating operation when said switch means is in "on" position, a communication circuit and an energizing circuit for connecting said instruments to said recording and control apparatus, relay means forming part of said control apparatus and connected in said communication circuit, said relay means being activatable when said switch means has been placed in "on" position, means at said instruments to interrupt said communication circuit to de-activate said relay means, marking means at said recording apparatus and operable by said relay means when said relay means is de-activated, power supply means under the control of said relay means for producing current flow in said energizing circuit when said relay means has been activated, current-responsive means at each of said instruments to be energized by said energizing circuit and arranged to exclude all instruments from said communication circuit except the instrument first operated for dictation purposes, and time delay means for said relay means to prevent the de-energization of said energizing circuit for a predetermined time period after actuation of said interrupting means.

13. A remotely-operated dictation system which includes centrally-located recording and control apparatus wherein a recording head is arranged for relative travelling movement with respect to a moving record, apparatus comprising, in combination, a plurality of remote dictator's instruments each including a transducer unit and an on-off device, circuit means for connecting said instruments to said recording and control apparatus, said circuit means being set up for communication with said recording apparatus when the on-off device at one of said instruments is placed in "on" position, operating means at said recording apparatus for conditioning said apparatus for reproducing operations so that recorded material can be transmitted back to said instruments, switch means at said recording apparatus and actuatable when said apparatus has been conditioned for reproducing operations, control means connected to said circuit means and to said switch means, said control means being operable when said switch means is in actuated position and concurrently one of said on-off devices is returned to "off" position, and indicating means operable by said control means to indicate that a dictator has placed his on-off device in "off" position with the recording apparatus conditioned for reproduce operations.

14. A remotely-operated dictation system which includes centrally-located recording and control apparatus wherein a recording head is arranged for relative travelling movement with respect to a moving record, apparatus comprising, in combination, a plurality of remote dictator's instruments each including a transducer unit and an on-off device, circuit means for connecting said instruments to said recording and control apparatus, said circuit means being completed when the on-off device at one of said instruments is placed in "on" position, operating means at said recording apparatus for conditioning said apparatus for reproducing operations so that recorded material can be transmitted back to said instruments, switch means at said recording apparatus and

11

actuable when said apparatus has been conditioned for reproducing operations, control means connected to said circuit means and to said switch means, said control means being operable when said switch means is in actuated position and concurrently all of said on-off devices are in "off" position, and signalling means operable by said control means for transmitting an audio signal to any dictator who subsequently places his on-off device in "on" position, to indicate to said subsequent dictator that the recording apparatus is conditioned for reproduce operations.

15. A remotely-operated dictation system which includes centrally-located recording and control apparatus wherein a recording head is arranged for relative travelling movement with respect to a moving record, apparatus comprising, in combination, a plurality of remote dictator's instruments each including a transducer unit and an on-off device, circuit means for connecting said instruments to said recording and control apparatus, said circuit means being completed when the on-off device at one of said instruments is placed in "on" position, operating means at said recording apparatus for conditioning said apparatus for reproducing operations so that recorded material can be transmitted back to said instruments, switch means at said recording apparatus and actuatable when said apparatus has been conditioned for reproducing operations, control means connected to said circuit means and said switch means, said control means being operable when said switch means is in actuated position and concurrently all of said on-off devices are in "off" position, and tone generating means operable by said control means to produce an audible signal at said recording apparatus to warn the attendant that a dictator has placed his on-off device in "off" position with the recording apparatus conditioned for reproduce operations.

16. A remotely-operated dictation system which includes centrally-located recording and control apparatus wherein a recording head is arranged for relative travelling movement with respect to a moving record, apparatus comprising, in combination, a plurality of remote dictator's instruments each including a transducer unit and an on-off device, circuit means for connecting said instruments to said recording and control apparatus, said circuit means being completed when the on-off device at one of said instruments is placed in "on" position, privacy means at said instruments arranged when actuated to exclude all of said instruments from said circuit means except the instrument first to complete said circuit means, operating means at said recording apparatus for conditioning said apparatus for reproducing operations so that recorded material can be transmitted back to said instruments, switch means at said recording apparatus and actuatable when said apparatus has been conditioned for reproducing operations, control means connected to said circuit means and said switch means and operable when said switch means is in actuated position and concurrently all of said on-off devices are in "off" position, said control means being arranged when operated to actuate said privacy means to prevent any dictator from establishing communication with said recording apparatus.

17. A remotely-operated dictation system which includes centrally-located recording and control apparatus wherein a recording head is arranged for relative travelling movement with respect to a moving record, apparatus comprising, in combination, a plurality of remote dictator's instruments each including a microphone, first, second and third lines connecting said instruments to said recording and control apparatus, said first and second lines serving as a communication circuit, function control means connected to said second and third lines and operable when a D.-C. path has been established between said second and third lines at one of said instruments, im-

12

pedance means connected between said first and second lines at each of said instruments and having an intermediate tap point, switch means at said instruments for connecting said intermediate tap point to said third line to establish a D.-C. path between said second and third lines, and operating means at said recording apparatus responsive to said function control means for performing a predetermined function whenever said switch means is actuated.

10 18. A remotely-operated dictation system which includes centrally-located recording and control apparatus wherein a recording head is arranged for relative travelling movement with respect to a moving record, apparatus comprising, in combination, a plurality of remote 15 dictator's instruments each including a microphone, first, second and third lines connecting said instruments to said recording and control apparatus, said first and second lines serving as a communication circuit, resistive means coupled between said first and second lines at each 20 of said instruments and having an intermediate tap point, switch means at said instruments for connecting said intermediate tap point to said third line to establish a D.-C. path between said second and third lines, power supply means for producing a flow of current through 25 said D.-C. path, playback control means connected to said second and third lines and operable by said current when said D.-C. path has been established between said second and third lines at one of said instruments, and playback means at said recording apparatus responsive 30 to said control means for conditioning said recording apparatus for playback operation whenever said switch means is actuated.

means is actuated.

19. A remotely-operated dictation system which includes centrally-located recording and control apparatus wherein a recording head is arranged for relative travelling movement with respect to a moving record, apparatus comprising, in combination, a plurality of remote dictator's instruments each including a microphone, first, second and third lines connecting said instruments to said recording and control apparatus, said first and second lines serving as a communication circuit, function control means connected to said second and third lines and operable when a D.-C. path has been established between said second and third lines at one of said instruments, a 35 potentiometer coupled between said first and second lines at each of said instruments, one side of said potentiometer being connected directly to said second line, switch means at said instruments for connecting the movable arm of said potentiometer to said third line to establish a D.-C. path between said second and third lines, and operating means at said recording apparatus responsive to said function control means for performing a predetermined function whenever said switch means 40 is actuated to complete said D.-C. path.

50

55 20. A remotely-operated dictation system which includes centrally-located recording and control apparatus wherein a recording head is arranged for relative travelling movement with respect to a moving record, apparatus comprising, in combination, a plurality of remote dictator's instruments each including a transducer, a communication circuit for connecting said transducers to said recording and control apparatus and including first and second wires, a voice-signal circuit coupled to said communication circuit for feeding voice signals therein to said recording head, power supply means for producing current flow in said communication circuit, control means at each of said instruments for selectively establishing two different current conditions in said communication circuit, first and second current-energizable means selectively actuatable by said two current conditions respectively, first circuit means connecting one terminal of said first current-energizable means directly to said first communication circuit wire, second circuit means connecting one terminal of said second current-energizable means directly to said second communication circuit wire, third

circuit means connecting the other terminals of said first and second current-energizable means in balanced relationship to said power supply means, and operating means selectively under the control of said current-energizable means to establish predetermined control functions at said recording and control apparatus in accordance with the setting of said control means.

21. A remotely-operated dictation system which includes centrally-located recording and control apparatus wherein a recording head is arranged for relative travelling movement with respect to a moving record, apparatus comprising, in combination, a plurality of remote dictator's instruments each including a transducer, a communication circuit for connecting said transducers to said recording and control apparatus and including first and second wires, a voice-signal circuit coupled directly across said first and second wires in symmetrical fashion and arranged to feed voice signals to said recording head, power supply means for producing current flow in said communication circuit, control means at each of said instruments for selectively establishing two different current conditions in said first and second communication circuit wires, first and second current-energizable means selectively actuatable by said two current conditions respectively, circuit means for connecting said current energizable means in series and directly across said first and second wires of said communication circuit in balanced relationship to said power supply means, and operating means selectively under the control of said current-energizable means to establish predetermined control functions at said recording and control apparatus in accordance with the setting of said control means.

22. A remotely-operated dictation system which includes centrally-located recording and control apparatus of the type wherein a recording head is arranged for relative travelling movement with respect to a moving record, said system comprising, in combination, a plurality of remote dictator's instruments each including a microphone, a communication circuit for connecting said microphones to said recording and control apparatus and including first and second electrically-conductive wires

extending from said apparatus to said instruments, a voice signal circuit forming part of said communication circuit and arranged to feed audio-frequency signals from said communication circuit wires to said recording head, said voice signal circuit including first and second input connections, first circuit means coupling one of said input connections directly to said first communication circuit wire, second circuit means coupling the other of said input connections directly to said second communication circuit wire, said first and second circuit means having identical impedance characteristics whereby said voice signal circuit is coupled to said communication circuit wires in a balanced fashion, power supply means for producing current flow in said communication circuit wires, first and second relay means connected in series with both said power supply means and said communication circuit wires to be operated by said current flow in said communication circuit wires, control means at each of said instruments for selectively establishing two different current conditions in said first and second communication circuit wires, said first and second relay means being selectively actuatable by said two current conditions respectively, and operating means under the control of said first and second relay means to establish predetermined control functions at said recording and control apparatus in accordance with the setting of said control means.

23. A dictation system as claimed in claim 22, wherein said voice signal circuit includes an audio transformer having a pair of primary windings, one terminal of each of said windings defining said first and second input connections respectively, and capacitor means coupling the other terminals of said windings together and serving to prevent the flow of direct current from said power supply means through said windings.
